United States Patent Office

Des. 187,158
Patented Feb. 2, 1960

187,158

POST LAMP

Betty Grace Page, Kansas City, Mo.

Application March 23, 1959, Serial No. 53,137

Term of patent 7 years

(Cl. D48—31)

Fig. 1.

Fig. 2.

Fig. 3.

Fig. 1 is a side elevational view of a post lamp, embodying my new design.

Fig. 2 is a front elevational view thereof.

Fig. 3 is a top plan view thereof.

The dominant features of my design reside in the portions shown in full lines.

I claim:

The ornamental design for a post lamp, as shown and described.
